UNITED STATES PATENT OFFICE.

HENRY A. WISE WOOD, OF NEW YORK, N. Y., ASSIGNOR TO CAMPBELL PRINTING PRESS & MANUFACTURING COMPANY, OF NEW YORK, N. Y., A CORPORATION OF NEW YORK.

WEB-SUPPLYING DEVICE FOR PRINTING-PRESSES.

SPECIFICATION forming part of Letters Patent No. 794,578, dated July 11, 1905.

Application filed March 4, 1898. Renewed November 8, 1904. Serial No. 231,955.

To all whom it may concern:

Be it known that I, HENRY A. WISE WOOD, a citizen of the United States, residing at New York, in the county of New York and State 5 of New York, have invented a new and useful Web-Supplying Device for Printing-Presses, of which the following is a specification.

The object of my invention is to provide a web-printing press with improved web-supplying devices arranged to automatically bring 10 a fresh roll into position to coöperate with the feeding-in devices of the press, so that a fresh web can be introduced without stopping the press.

15 To these ends my invention consists of the parts and combination of parts, as hereinafter described, and more particularly pointed out in the claims at the end of this specification.

In the accompanying drawings, Figure 1 is 20 a side view, partially in section, illustrating a web-supplying device constructed according to my invention. Fig. 2 is a sectional view taken on the line 2 2 of Fig. 1. Fig. 3 is a sectional view taken on the line 3 3 of Fig. 1. 25 Fig. 4 is a detail view to be hereinafter referred to. Figs. 5 to 7, inclusive, are diagrammatic views illustrating the operation of the device; and Fig. 8 is a side view, partially in section, illustrating a modified form 30 of construction.

In the ordinary forms of web - printing presses now employed for printing newspapers or similar products a web-roll is usually mounted in bearings on the side frames of the 35 press and is provided with suitable tension devices for preserving the proper tension of the web while the same is being drawn into the press. When a web-roll is nearly exhausted, it is now ordinarily the practice to 40 stop the press in order to permit the expiring web to be severed, to remove the stub or expired web-roll from its bearings in the side frame, then to mount a fresh web-roll in the bearings, and to paste the end of the fresh 45 web to the end of the expiring web, so as to permit the end of the fresh web to be drawn through the machine. These operations have heretofore ordinarily been performed by

hand, and it has required considerable time to accomplish the transfer of the web-rolls. 50

The especial object of my invention is to provide improved devices for automatically connecting a fresh source of web-supply, as the end of the fresh web-roll, with the printing mechanism, so that as the expiring source 55 of web-supply gives out a fresh supply will be automatically introduced. Specifically, I provide mechanism for automatically introducing the end of a fresh roll into the feeding-in device of the printing-press and for 60 automatically stopping the supply from the web - roll which is nearly exhausted. The feeding-in devices may be of the ordinary or approved construction, comprising a feeding-in drum coöoperating with suitable feeding- 65 tapes, which unwind the web, as required in the operation of the press. The feeding-in device is preferably mounted in overhanging main frames of the press, and below the feeding device I provide a framework for supporting a 70 plurality of web-rolls. The side frames of this framework are preferably provided with inclined tops for supporting the shafts of the web - rolls. Mounted in the framework are suitable sprocket wheels and chains, having 75 open boxes or forks for engaging the web-roll shafts. Turning with one of the sprocket-wheels is a stop-disk, and coöperating with the stop-disk is a brake-lever having an abutment 80 for engaging suitable stops or projections on the stop-disk to hold the desired web-roll in position to coöperate with the feeding-in device of the press. When the brake-lever is released or moved out of engagement with the stop-disk, the weight of the web - rolls will 85 cause them to roll down on their inclined supports until one of the abutments of the stop-disk again engages with the brake - lever. The motion or travel of the web-rolls down their inclined support can be accurately controlled by varying the pressure exerted on 90 the brake-lever. Connected with and actuated from the brake-lever I provide connections for severing the expiring web and for tucking the end of the fresh web into the feeding-in device. If desired, I may provide also 95

an automatic pasting mechanism for depositing paste upon the end of the fresh web, so that the same will be automatically fastened to the expiring web.

5 Referring to the drawings and in detail, A designates one of the overhanging side frames of a printing-press. Journaled in the side frames A is a feeding-in drum 10, coöperating with which are the ordinary tapes 11, which pass around the tape-rolls 12. A framework B, as indicated by dotted lines in Fig. 1, is located beneath the overhanging side frames A in position to support a plurality of web-rolls. As illustrated, the framework B forms an inclined support for three web-rolls, a fresh web-roll being indicated by the reference-numeral W², the web-roll from which the web w is being drawn into the press being indicated by W and an expired web-roll being indicated by W'. The shafts 13 of the web-rolls W, W', and W² rest upon and are supported by the side frames B. Secured upon the shafts 13 I provide gears 14, which are arranged to engage suitable tensioning and registering devices, as hereinafter described.

Mounted in the frames B are sprocket-wheels 15, which carry sprocket-chains 16. Carried by the sprocket-chains 16 and supported by ledges 170, as most clearly shown in Fig. 3, are open boxes or forks 17. Turning with one of the sprocket-wheels 15 is a stop-disk 18, having abutments or projections 180.

35 A brake-lever 19 is journaled in the framework B and is provided with a catch or abutment 190 for engaging the stops 180 of the stop-disk 18. By means of this construction it will be seen that when the brake-lever 19 is raised out of engagement with the stop-disk 18 the web-rolls will move down their inclined support through the influence of gravity until the brake-lever 19 is again brought into engagement with the stop-disk 18. This motion or transfer of the web-rolls can be accurately governed by varying the pressure exerted upon the brake-lever 19.

50 The tensioning and registering devices co-operating with the gears 14 of the web-roll shaft 13 are most clearly illustrated in Figs. 1 and 3. As shown, a gear 20, having flaring guides or flanges, is secured upon a shaft 21, journaled in one of the side frames B. A disk is secured on the outer end of the shaft 21, and a friction brake or strap 22 is arranged to engage with the disk, the friction between the disk and strap being capable of adjustment by means of a hand-wheel 25. This hand-wheel is fitted upon a shaft the end of which 55 is threaded into the projecting end of one brake-strap and which fits loosely in the other brake-strap, a collar being also arranged on said shaft to bear on this brake-strap. By thus turning the hand-wheel 25 the brake can be adjusted. The shaft 21 can be slightly

shifted longitudinally to bring the web-roll into alignment with the printing-press by means of a threaded bolt connected to the friction-strap 22 and provided with a hand-wheel 23. This shaft is threaded into the frame, as shown, and the brake-shoes are loosely hung thereon between said hand-wheel 23 and a collar secured on said shaft. By turning the hand-wheel 23 it will be seen that the brake-shoes, and thereby the shaft 21, will be moved axially. This will also move the gear 20 axially, and by means of the flanges on the side of said gear the gear 14, and thereby the web-roll W, can be adjusted axially. This adjustment is a slight one—that is, it is used only to adjust the web-roll so that the web will assume the proper lateral position in the printing-press.

70 A link 26 connects the brake-lever 19 with an arm 27, extending from a rock-shaft 28, journaled in the frames A. Secured upon the rock-shaft 28, outside of the framework A, are arms 29. Extending down from the arms 29 are arms 30, carrying a pasting-roller 31, which coöperates with a paste-fountain 32. 75 The shaft of the paste-roller 31 is mounted in suitable slots or guides 33 in the side frames A, so that said paste-roller will move in a curved path to properly deposit paste upon the end of a fresh web, which may be supported in place on the tucker-blade 34. The tucker-blade 34 is carried by curved arms extending down from a rock-shaft 36. A latch 41 is arranged to hold the tucker-blade 34 80 down in its normal position against the tension of a spring 37, which normally tends to throw the tucker-blade up into engagement with the feeding-in device. A pawl 40 for releasing the latch 41 is journaled on one of the arms 30, as most clearly illustrated in Fig. 4. 85 To restore the tucker-blade to its normal position after the same has been brought into operation to tuck the end of a fresh web into the feeding-in device, I provide a slotted link 38, which extends down from one of the arms 29 to engage a pin carried by an arm 39, extending from the rock-shaft 36. When the arms 29 are in their raised position, the tail-piece of the pawl 40 will engage with a stop 42 to release the latch 41, so that said latch 90 may hold the tucker-blade in its normal position until the operation of said tucker-blade is again required. A pivoted knife or web-severing device 43, which is normally held out of engagement with the web w by means of a spring 44, is arranged in the path of the tucker-blade, so that when said tucker-blade is thrown up by the operation of its spring 95 the knife 43 will be brought into engagement with the web of the expiring web-roll, so as 100 to cut off or sever the expiring web.

105 A chain 16 and set of boxes 17 are preferably arranged at each side or on each frame of the machine, so that the shafts 13 of the web-rolls will be controlled from both sides. 110

The operation of a web-supplying device for printing-presses as thus constructed is most clearly illustrated in Fig. 1 and in the diagrammatic views of Figs. 5 to 7. In order to replace an expiring web-roll with a fresh web-roll, the brake-lever 19 will be raised, so as to move its abutment 190 out of engagement with an abutment 180 on the stop-disk. When the brake-lever 19 is raised to its highest position, as illustrated in Fig. 6, the paste-roller 31 will be moved down, so as to deposit paste on the end of the fresh web carried by the tucker-blade 34. As the brake-lever 19 is moved down to the position illustrated in Fig. 7 the paste-roller will be moved up, so that the pawl 40 will release the latch 41, and the spring-actuated tucker-blade will insert the end of the fresh web into the feeding device of the press, at the same time operating the web-severing device to cut off the expiring web. When the brake-lever 19 again resumes its normal position, the slotted link 36 will draw the tucker-blade back to its normal position, and the latch 41 will be released, the parts again assuming their normal position, as illustrated in Fig. 1. It will thus be seen that by manipulating a single lever an expiring web-roll can be removed, a fresh web-roll brought into position to coöperate with the feeding-in devices of a press, paste may be deposited upon the end of a fresh web, which will then be properly inserted into the feeding-in device of the press, and the expiring web will be severed or cut off.

A device as thus constructed is substantially automatic in action, since when the lever 19 is once raised to its highest position to release the disk 18 the parts will all automatically operate and be restored again to their normal position, as the lever is brought back to its normal position pressing on the disk 18.

In some cases I contemplate simplifying my web-supplying device for printing-presses by dispensing with the automatically - acting paste-roller, and I have illustrated such a construction in Fig. 8. Referring to said figure, A designates one of the side frames of a printing-press. Journalized in the side frames A, as heretofore described, is the usual feeding-in drum 10, coöperating with which are the tapes 11, passing over the tape-rollers 12. Instead of employing separate side frames to form a support for the web-rolls the side frames A may be extended, as at A'. The upper edges of the extending parts A' are inclined to form a support for the shafts 13 of the web-roll W, from which the web w is being drawn into the press and of the fresh web-roll W'. Mounted in the extensions A' of the side frames A are the sprocket-wheels 50, carrying the chains 51, which chains 51 are provided with the open-topped boxes or forks 52, substantially as hereinbefore described.

Secured upon the sprocket-wheel shaft, near the end of the press, is the stop-disk 53, co-operating with which is the brake-lever 54. A link 55 forms a direct connection between the brake-lever 54 and the tucker 56. A web-severing device or knife 57 is located in position to be operated by the tucker 56 and is normally held back out of the way by means of a spring 58. By raising the brake-lever 54 the web-rolls will be released, so as to roll down their inclined support, while at the same time the end of the fresh web will be introduced into the feeding-in device and the expiring web will be severed. The side frames A are preferably provided with bearings 59 for supporting the shaft 13 of an expired web-roll until it may be convenient to remove the same from the press. It will be seen that this form of web-supplying device for a printing-press is simple in its construction and positive in its action, and in many instances I preferably employ the same, as paste may be readily applied to the end of the web to be inserted when the end of the same is connected to the tucker-blade.

I do not broadly claim in this case mechanism for inserting the end of a fresh web and discontinuing the supply of web from an expiring web-roll, as this is claimed broadly in my companion case filed on even date herewith, Serial No. 672,555.

I am aware that changes may be made in the construction of my web-supplying devices for printing-presses without departing from the scope of my invention as expressed in the claims. I do not wish, therefore, to be limited to the forms which I have shown and described; but

What I do claim, and desire to secure by Letters Patent of the United States, is—

1. The combination with a web-feeding device, of a tucker coöperating therewith, a web-severing device, and means for automatically operating the tucker to introduce the end of a fresh web into the feeding device and to operate the severing device.

2. The combination of a web-feeding device, and means for automatically bringing a web-roll into position to coöperate therewith, and for introducing the end of the web drawn from this web-roll into the web-feeding device.

3. The combination of a web-feeding device, and means for automatically removing an expiring web-roll, and means for bringing a fresh web-roll into position to coöperate therewith, and for introducing the end of the web drawn from this web-roll into the web-feeding device.

4. The combination of a web-feeding device, a tucker-blade, and means for automatically removing an expiring web-roll and for bringing a fresh web-roll into position.

5. The combination of a web-feeding device,

a web-severing device, a tucker-blade, and means for automatically replacing an expiring web-roll with a fresh web-roll.

6. The combination of a web-feeding device, 5 means for automatically bringing a web-roll into position to coöperate therewith, and means for fastening the end of the fresh web to the expiring web before the latter reaches the web-feeding device, so that the joint will pass through the web-feeding device.

7. The combination of a web-feeding device, a tucker-blade, and a pasting device for fastening a fresh web to an expiring web.

8. The combination of a web-feeding device 15 and an inclined support for a plurality of web-rolls, and controlling devices for holding the desired web-roll in position to coöperate with the web-feeding device, and for introducing the end of a fresh web into the feeding device.

20 9. In a web-roll-supplying device for printing-presses, the combination of the web-feeding device, sprocket wheels and chains, boxes carried by the chains, for engaging the web-roll shafts, means for controlling the motion 25 of the chains to bring a fresh web-roll into place, and means for introducing the end of the fresh web into the web-feeding device.

10. In a web-roll-supplying device for printing-presses, the combination of the sprocket 30 wheels and chains, boxes carried by the chains, for engaging the web-roll shafts, and a stop-disk and brake for controlling the motion of the chains to bring a fresh web-roll into place.

11. The combination of an inclined support 35 for a plurality of web-rolls, the sprocket wheels and chains having means for engaging the web-roll shafts, a stop-disk turning with one sprocket-wheel, and a brake-lever coöperating with said stop-disk.

40 12. The combination of a framework forming an inclined support for a plurality of web-rolls, the sprocket wheels, and chains, having boxes for engaging the web-roll shafts, a stop-disk and brake-lever for controlling the 45 sprocket-chain, and web tensioning and registering mechanism mounted in the framework in position to coöperate with gears on the web-roll shaft.

13. The combination of an inclined support 50 for a plurality of web-rolls, a brake-lever for controlling the motion of said web-rolls, a web-feeding device, a tucker-blade, and connections for operating said tucker-blade from the brake-lever.

55 14. The combination of an inclined support for a plurality of web-rolls, a brake-lever controlling the motion of said web-rolls, a web-feeding device, a tucker-blade, a pasting device, and connections for operating the pasting 60 device and tucker-blade from the brake-lever.

15. The combination of an inclined support for a plurality of web-rolls, a brake-lever for controlling the motion of said web-rolls, a web-feeding device, a tucker-blade, a pasting 65

roller, a severing device for the expiring web, and connections from the brake-lever for operating the pasting device, tucker-blade and web-severing device.

16. The combination of a web-roll-supply 70 mechanism, a lever controlling said web-roll-supplying device, a spring-controlled tucker-blade, a latch for holding said tucker-blade in its normal position, and releasing and resetting connections actuated from said lever. 75

17. The combination of a web-roll-supplying mechanism, a controlling-lever therefor, a pasting-roller, a spring-pressed tucker-blade, connections for releasing and resetting said tucker-blade and for operating the paste-roller 80 from the controlling-lever.

18. The combination of a web-roll-supplying mechanism, a controlling-lever therefor, a paste-roller, a spring-pressed tucker-blade, releasing and resetting connections for the 85 tucker-blade, and operating connections for the paste-roller actuated by said lever, and a web-severing device actuated by the tucker-blade.

19. The combination of an inclined support 90 for a plurality of web-rolls, the sprocket wheels and chains for controlling the motion of said web-rolls, a web-feeding device, a tucker-blade, a stop-disk and brake-lever controlling the sprocket-chains, and connections 95 from the brake-lever for operating the tucker-blade, said brake-lever and stop-disk being so arranged that when the brake-lever is raised to operate the tucker-blade, the stop-disk will be released. 100

20. The combination of a feeding-in device of a printing-press, means for replacing an expiring web-roll with a fresh web-roll, means for inserting the end of the fresh web into the web-feeding device, and a single handle 105 for bringing said instrumentalities into action.

21. The combination of a feeding-in device, of a web-printing press, means for replacing an expiring web-roll with a fresh web-roll, means for inserting the end of the fresh web 110 into the web-feeding device, a web-severing device for cutting off the expiring web, and a single handle for bringing said instrumentalities into action.

22. The combination of a web-feeding device of a printing-press, means for replacing an expiring web-roll with a fresh web-roll, means for depositing paste upon the fresh web and for introducing the end of said web into the feeding device, means for severing 115 the expiring web, and a single handle connected to bring said instrumentalities into action. 120

In testimony whereof I have hereunto set my hand in the presence of two subscribing witnesses.

H. A. WISE WOOD.
